SAFETY HELMET

Malcolm D. Sinclair, 2279 Riverwood Place, St. Paul, Minn. 55111, Andrew S. Fraser, 120 Ashley Road, Hopkins, Minn. 55343, and Alwin J. Stahel, New Brighton, Minn.; said Stahel assignor to said Sinclair and said Fraser

Filed Sept. 16, 1968, Ser. No. 13,550

Term of patent 14 years

Int. Cl. D2—03

U.S. Cl. D2—231

FIGURE 1 is a view in top plan of a safety helmet showing our new design;

FIGURE 2 is a view in side elevation thereof, the side opposite that shown being substantially a mirror image;

FIGURE 3 is a view in rear elevation thereof;

FIGURE 4 is a view in front elevation thereof; and

FIGURE 5 is a view in bottom plan thereof.

We claim:

The ornamental design for a safety helmet, substantially as shown and described.
